UNITED STATES PATENT OFFICE

121,137

DESIGN FOR A BURIAL VAULT

Robert F. Donahey, Shaker Heights, Ohio

Application August 21, 1939, Serial No. 86,813

Term of patent 14 years

To all whom it may concern:

Be it known that I, Robert F. Donahey, a citizen of the United States and a resident of Shaker Heights, county of Cuyahoga and State of Ohio, have invented a new, original, and ornamental Design for a Burial Vault, of which the following is a specification, reference being had to the accompanying drawing, forming a part thereof.

Fig. 1 is a perspective view of a burial vault showing my new design, and

Fig. 2 is a section taken through the end closing member on the plane 2—2 of Fig. 1, looking in the direction of the arrows.

Both ends of the vault are alike.

The characterizing features of my design reside in a burial vault of the configuration shown having end closing members each comprising a flat, relatively narrow border of substantially uniform width circumscribing a dome-shaped central area, as shown.

I claim:

The ornamental design for a burial vault, as shown and described.

ROBERT F. DONAHEY.
